UNITED STATES PATENT OFFICE

JOSEPH T. TWEEDALE, OF YARDVILLE, NEW JERSEY, ASSIGNOR TO HUSSONG DYEING MACHINE COMPANY, OF GROVEVILLE, NEW JERSEY, A CORPORATION OF NEW JERSEY

DYEING MACHINE HEAD

Application filed December 9, 1929. Serial No. 412,778.

This invention relates to dyeing machine heads and more particularly to the provision of a dyeing machine head of such construction that a unitary drive may be provided for the several propellers of the dyeing machine and a mounting provided therefor permitting ready dismantling for repairs or replacements.

In dyeing machines as at present constructed each propeller shaft projects through the head of the machine and the upper ends of these shafts are equipped with gears, one of which is driven directly from a suitable drive and the other of which is driven from the first gear. It is obviously impossible in employing such a construction to connect a plurality of machines in series as the strain of all succeeding propeller drives is imposed upon each of the drives and the first drive of a series would have to stand such immense strains that it would rapidly deteriorate if it were at any time operative. Furthermore, a construction of this character necessitates the provision of a number of short shafts which are difficult to mount and to maintain in repair and dismantling of any machine would result in a shutting down of the succeeding machines and the consequent loss of output. In addition to the foregoing there is a considerable monetary loss involved in the propeller shaft arrangement now provided in that the substances in which the propeller shafts operate cause the same to deteriorate rapidly and necessitate frequent replacements.

Accordingly, an important object of this invention is the provision of a structure permitting simultaneous drive of the propeller shafts of a number of machines from a single source of power which is so constructed that repairs can be made to one of the machines without interrupting the operation of the remaining machines and which will permit of the sectional removal of the propeller shafts so that only that portion of the pro-

peller shaft which has deteriorated need be discarded.

A further object of the invention is to provide a construction of this character in which the gearing employed can be conveniently housed and operated in lubricant, thus permitting the economical use of high grade bearings for the operating shaft and propeller shafts.

These and other objects I attain by the construction shown in the accompanying drawings wherein, for the purpose of illustration, I have shown a preferred embodiment of my invention and wherein:

Fig. 1 is a side elevation partially in section of a dyeing machine head constructed in accordance with my invention;

Fig. 2 is a plan view thereof partially in section;

Fig. 3 is a detail sectional view through a propeller shaft coupling; and

Fig. 4 is a semi-diagrammatic plan illustrating use of the apparatus in connection of a plurality of dyeing machines.

Referring now more particularly to the drawings, the numeral 10 generally designates a cover or base plate having arising therefrom adjacent one end thereof a standard 11 for a motor 12. The cover is provided with spaced openings 13 for the passage of propeller shafts 14 and mounted upon the base 10 over each opening is a casting 15 including a base wall 16 carrying packings 17 for the propeller shaft. The casting 15 further includes an upstanding annular side wall, the upper end of which forms, together with a transverse wall 18, a cup-shaped housing the bottom of which has a packing gland 19 for the passage of the propeller shaft. The propeller shaft within the cup-shaped housing is equipped with a hypoid spiral beveled gear 20 which meshes with a pinion 21 secured to a shaft 22 mounted in bearings 23 supported from the side wall of the casing. Shaft 22 within each

housing is reduced affording step shoulders mounting the bearings 23. Pinion 21 is secured to the shaft at this reduced portion and is equipped with sleeves 24 extending between opposite ends of the pinion and the bearings. At the smaller end of the reduced portion a nut 25 threaded upon the shaft clamps the adjacent bearings 23 against the end of the associated sleeve and thus serves to compact the entire assemblage against the first shoulder 26 of the stepped reduction. The bearing 23 adjacent the nut 25 is preferably mounted in a cup carried by the cup-shaped housing and held against longitudinal movement with relation thereto.

A cap 27 is provided for the cup-shaped housing, the upper end of this cap having a gland for packings 28 engaging the upper end of the propeller shaft above the gear. The upper end of this cap is recessed to provide a seat for bearing 29 for the propeller shaft and a cap is provided for this recess as indicated at 30.

Propeller shaft 14 consists of two sections 31 and 32, of which section 31 mounts the gear 20, is mounted at its upper end in the bearing 29 and at its lower end is mounted in the bearings 33 carried by the base plate 18 of the casting. Section 31 has its lower end recessed for the reception of a reduced extension 34 formed upon the section 32 and is secured to the section 32 by means of tapered pins 35 held in position by removable blind screws 36. These screws and the tapered pins are accessible for removal through openings 37 formed in the side wall of the casting below partition 18 and it will be obvious that by loosening the hold-down screws 38 of the cap and releasing coupling 39 which connects shaft 22 to the armatured shaft 40 of the motor 12 the entire shaft and the section 31 of the propeller shafts may be removed as a unit. In event the section 32 of the propeller shaft deteriorates as it will in use, this section may be removed for replacement by merely removing the tapered pins and withdrawing the section 32 when it may be substituted for by a new section without the necessity of tearing down the entire structure or throwing away the entire propeller shaft.

It will also be obvious that by equipping the free end of shaft 22 with the coupling 39-a as suggested in Fig. 4, this shaft may be connected to similar shafts of the heads of other machines so that a group of the machines may be arranged in series. The required shutdown of the series for replacement of a propeller shaft will be a very short interval due to the accessibility of the connections and to the two-part construction of the shaft. In event it becomes necessary to remove the gears of a head of the series, this may be readily accomplished by simply disconnecting the couplings 39 and 39-a and

removing the hold-down bolts of the heads, after which the shaft section 22 may be substituted for by a replacement shaft section until necessary repairs to the removed parts have been completed.

Since the structure illustrated is capable of a considerable range of change and modification without in any manner departing from the spirit of my invention, I do not wish to be understood as limiting myself to such structure except as hereinafter claimed.

I claim:

1. In a dyeing machine head, a base having an opening, a casting seated upon the base in surrounding relation to the opening, upper and lower partitions in the casting, each having a packing gland aligned with the base opening, a propeller shaft formed in two coupled sections, each section extending through one of said glands, the coupling being disposed between the sections, the casting having openings between the partitions permitting access to the coupling.

2. In a dyeing machine head, a base having an opening, a casting seated upon the base in surrounding relation to the opening, upper and lower partitions in the casting, each having a packing gland aligned with the base opening, a propeller shaft formed in two coupled sections, each section extending through one of said glands, the coupling being disposed between the sections, the casting having openings between the partitions permitting access to the coupling, the upper partition being spaced below the upper end of the casting, a cap for the casting combining with the partition to provide a housing and to mount bearings for a transversely extending shaft and gears for connecting the transversely extending shaft and propeller shaft within said housing.

3. In a dyeing machine head, a base, a pair of propeller shafts extending upwardly through the base, a motor standard mounted on the base, a hypoid gear carried by each propeller shaft adjacent the upper end thereof, a longitudinally extending shaft projecting adjacent each of said gears, having a pinion for co-action therewith, a motor carried by the standard and coupled to said shaft to drive the same and a casting associated with each propeller shaft providing bearings for the shaft at points above and below the gear thereof, said castings having openings in the side walls thereof, the propeller shafts being each formed in two coupled sections, the coupling of which is accessible through the opening of the associated casting.

4. In a dyeing machine head, a base having an opening, a casting seated upon the base in surrounding relation to the opening, upper and lower partitions in the casting, each having a packing gland aligned with the base opening, a propeller shaft formed in two coupled sections, each section extending through

one of said glands, the coupling being disposed between the sections, the casting having openings between the partitions permitting access to the coupling, the upper partition being spaced below the upper end of the casting, a cap for the casting combining with the partition to provide a housing and to support bearings for a transversely extending shaft, and gears for connecting the transversely extending shaft and propeller shaft within said housing, the upper end of the propeller shaft having bearings in said cap.

JOSEPH T. TWEEDALE.
